AUTOMATIC LOCK SLIDER FOR SLIDE
FASTENERS

Claude Disinger, South Plainfield, and Frederick Ulrich, Jersey City, N. J., assignors to Conmar Products Corporation, Newark, N. J., a corporation of New Jersey

Application January 27, 1945, Serial No. 574,894

12 Claims. (Cl. 24—205.14)

1

This invention relates to an improved automatic lock slider for slide fasteners.

Slide fasteners comprise two mating slide fastener stringers (tapes with mounted fastener elements) brought into and out of meshing or mating relation by the movement of a so-called slider through the slide channel of which the stringers slide or move. It is necessary to provide a suitable locking device for the slider to prevent the stringers accidentally opening during use. According to one type of lock slider the locking member is made so as to be entirely automatic in its locking operation. The common form of automatic lock slider embodies a locking member on the slider which is normally held in its locking position by a spring and which is moved against the action of the spring by a pull element connected to the locking member. Our present invention relates to an improved automatic lock slider of this type.

The prime objects of our invention center about the provision of an automatic lock slider featured by the following improvements:

1. The lock slider is composed only of three elements, namely, the slider, the locking member, and the pull element. These three parts are so designed and constructed according to the present invention that they are capable of being most conveniently and quickly assembled.

2. To achieve this the locking member embodying its supported part, its locking detent and the spring for actuating the same is made as a unitary piece with all these parts preferably integral and preferably shaped up from sheet metal. The use of separate springs with the difficulties of handling and slider assembling incident thereto is obviated.

3. Despite the limitations imposed by the small space available on a slider, the unitary locking member is so constructed that ample operating leverages are obtained for effecting the automatic locking operation and the unlocking operation of the slider. In accomplishing this, the locking member and its mounting on the slider are so designed that the locking member leverage and the effective spring leverage each extend over a substantial, such as the greater part, of the slider length, and

To the accomplishment of these objects and such other objects as may hereinafter appear our invention is directed to the automatic lock slider and the component combinations thereof

as sought to be defined in the appended claims and as described in the following specification taken together with the accompanying drawings in which:

5 Fig. 1 is a front elevational view, with a part broken away, of the lock slider of the present invention;

10 Fig. 2 is a view thereof taken in cross-section in the planes of line 2—2 of Fig. 1 and showing the locking member in its locking position;

15 Fig. 3 is a perspective exploded view of the front wing of the slider and the locking member and pull device therefor;

20 Fig. 4 is a front elevational view, with a part broken away, of a modified form of the lock slider of the present invention;

25 Fig. 5 is a view of Fig. 4 taken in cross-section in the planes of the broken line 5—5 of Fig. 4, and

20 Figs. 6 and 7 are views similar to Figs. 4 and 5, but showing a modification of the structure of Figs. 4 and 5.

30 Referring now more in detail to the drawings and having reference first to Figs. 1 and 2 thereof, the invention is shown applied to a conventional slide fastener comprising the slider S provided with the interior slide channel C and the two stringers s, s, the latter each comprising a beaded tape t with the spaced slide fastener elements f, f

35 mounted thereon, the said stringers being adapted to be brought into and out of meshing or mating relation by the up and down movement of the slider S through the slide channel C of which the stringers slide or move. The slide channel C is a Y-shaped channel as best shown in Fig. 1 through the stem of which the fastener elements move when meshed or interengaged and through the Y branches of which the fastener elements move when they are disengaged, as is most clearly shown in Fig. 1 of the drawings.

40 According to one form of known structure, the slider S comprises a rear or bottom wing section 20 and a front or top wing section 22 which are secured together as by being spot welded at their upper termini 24 and 26. The bottom wing 20

45 comprises a body wall provided with the inturned opposite flanges 28, and similarly the top wing 22 comprises a body wall provided with the inturned opposite slide flanges 30. These two slider wings 20 and 22 as described define the interior Y-shaped slide channel C for the slide fastener

50 stringers. Thus far the construction described is

a conventional form of slide fastener. By moving the slider downwardly, the slide fastener is opened, and by moving the slider upwardly, the slide fastener is closed.

The locking member of the lock slider is mounted on the front wing 22 of the slider. For this purpose the front wing is provided with a mounting means for the locking member, preferably in the form of an elongated lug 32 shaped up by suitable coining operations from the metal of the front slider wing, the said lug being given the configuration best shown in Fig. 3 of the drawings. This lug forms a bridging member bridging the top and bottom wall portions of the slider wing 22 and spaced from the side wall portions thereof by two elongated orifices 36 and 38, which orifices open into the slider channel C. The lug 32 forms a solid piece having a top wall 40 and the two side walls 42 and 44, pierced at the top to provide a pintle bearing bore 46.

The locking member L comprises essentially a front arm 48 and at least one rear arm, two such rear arms 50 and 52 being provided in the exemplified construction, united at their bottom ends 54 and free at their other or top ends, said arms being movable resiliently one with respect to the other, said locking member having at least one detent 56 adjacent its bottom end, and in the exemplified construction two such detents 56 and 58 are provided, both detents projecting into the slider channel C. In the preferred construction shown, these detents are formed one at the bottom end of the rear arm 50 and the other at the bottom end of the rear arm 52, both being staggered vertically so as to cooperate with a staggered pair of slide fastener elements f, f of the stringers, as best shown in Fig. 2 of the drawings. The resilient relative motion between the front arm 48 and the rear arms 50 and 52 is preferably accomplished by making either the front arm or the rear arms resilient; and in the construction shown, the front arm 48 is formed as a rigid element and, preferably, both rear arms 50 and 52 are formed as and define the resilient arms of the locking member.

Preferably these three components parts of the locking member, namely, the front rigid arm 48, the rear resilient arm or arms 50, 52, and the locking detents 56, 58, comprise a unitary piece as best shown in Fig. 3 of the drawings, and are all integral; and this unitary piece is formed, by bending and stamping operations, into the shape best shown in Fig. 3 of the drawings. We prefer to fashion this unitary locking member out of an alloy such as copper-beryllium, the resilient arms, 50, 52, being tempered for their resilient action after the element has been shaped into the desired form.

In its more specific embodiment, the locking member L is shaped so that its front arm 48 comprises a rigid elongated cap having a front wall 60 and rearwardly turned side walls 62 and 64, the resilient arms 50, 52 and their detents 56, 58 being formed integrally with these side walls. The side walls 62 and 64 are also shaped so as to provide the cam shaped openings 66 and 68 for receiving the opposite prongs 70 and 72 of a pendent pull device 14. The side walls 62 and 64 are also pierced at their upper ends to provide the pintle receiving openings 76 and 78. The resilient arms 50 and 52 are preferably inset or inturned at their upper ends to provide bearing seats 80 and 82 therefor.

The locking member L is assembled to the slider S by merely placing the locking member

into the position shown in Fig. 2 of the drawings and by inserting the hinge pintle 84 through the aligned pintle bearing openings and bore 76-78, 48. The assembling of these parts will also be evident from considering the exploded view of Fig. 3 of the drawings. When so assembled, the cap-shaped rigid arm 48 is mounted on and envelops the mounting lug 32, the resilient arms 50 and 52 of the locking member projecting through the elongated orifices 36 and 38 of the front slider wing 22 with the detents 56 and 58 thereof extending into the slider channel C for engagement by and with the stringer elements f, f. The free bearing ends 80, 82 of the resilient arms 50 and 52 are thereby arranged for engagement at a point upwardly of the hinge pintle fulcrum whereby a force applied thereto will tend to contract the arms of the locking member to move the locking member resiliently to its locking position as shown in Fig. 2 of the drawings. In the structural embodiment shown in Figs. 1 to 3, the engagement of the free ends 80 and 82 of the resilient arms is effected by and with a wall part of the front slider wing 22. For this purpose the front slider wing at the top ends of each of the orifices 36 and 38 thereof is shaped to provide a bearing ledge 86 (see Fig. 2) engageable by the resilient arm bearing seats (80, 82). The bearing ledges 86 and the hinge pintle fulcrum mounting of the locking member are so disposed that normally a tension is applied to the resilient arms 50 and 52 tending to deflect these arms frontally of the slider and thereby tending to contract these arms with reference to the rigid arm 48, the bearing points for the resilient arms and the fulcrum for the locking member being so disposed that it is by this contraction that the locking member is normally and automatically moved to its locking position as best shown in Fig. 2.

The locking member L is thus, under the resilient action of its rear resilient arms 50 and 52, normally and automatically moved to its locking position. When a cross pull is exerted upon the upper ends of the stringers s, s, tending to open the stringers, the slider S tends to move downwardly relatively to the stringers, thereby bringing the teeth or detents 56 and 58 (if they are not yet in engagement with the slide fastener elements) into locking engagement with the slide fastener elements f, f (see Fig. 2). The slider is unlocked in the usual way by either a downward pull (during opening of the slide fastener) or an upward pull (during closing of the slide fastener) exerted on the pull device 14. During a downward pull thereof, this pull device moves downwardly from the position shown in Fig. 2, during which movement the prongs 70, 72 thereof engage and ride over the bottom portions of the cam openings 66 and 68, thus causing the locking member L to move outwardly about its fulcrum or pivot hinge 84 against the resilient action of the resilient arms 50 and 52, the resilient tension of which is increased by the further contraction of the arms of the locking member as the latter is moved to its unlocking position. During an upward pull of the pull device 14 the prongs 70, 72 thereof engage the cam openings at the bend 88 thereof (see Fig. 2), and the locking member L is similarly moved about its fulcrum or pivot hinge against increasing tension of the resilient arms to its unlocking position or to a position where the detents 56 and 58 freely ratchet over the slide fastener elements f, f. Upon manual release of the pull 14 after either the

downward or upward pulling operation, the locking member L automatically returns to its Fig. 2 locking position.

In the modified embodiment of the invention shown in Figs. 4 and 5 of the drawings the force acting upon the resilient arm or arms of the locking member is derived from engagement with the fastener elements of the stringers. Both the slider and the locking member are modified accordingly, the parts thereof being otherwise similar to the parts of the structural embodiment of Figs. 1 to 3 of the drawings, the similar parts being designated by similar but primed reference characters. In this embodiment of the invention the principles involved in the Figs. 1 to 3 structure are combined with principles of construction and operation embodied in the automatic lock slider disclosed in the patent to Mikulas & Jones No. 2,360,437, patented October 17, 1944.

In this modification of Figs. 4 and 5 the slider S', the lug 32', and their associated parts, are substantially the same as in the slider of Figs. 1 to 3 with the exception that the orifices 36' and 38' instead of being longitudinally linear are formed with the diverging branches 90, 92 which run in alignment with the Y branches of the slider channel, as best shown in Fig. 4 of the drawings, both of these orifice branches 90 and 92 opening into the Y branches of the slider channel. The locking lever L' embodies a form and shape similar to that of the Figs. 1 to 3 structure, the essential difference being that the rear resilient arms 50' and 52' instead of being longitudinally linear are also formed with corresponding diverging branches 94 and 96 projecting through the diverging orifice branches 90 and 92 having upper free ends which are adapted to engage and be engaged by the separated stringer fastener elements f', f' moving through the slider branch channels. This lever L' may also be provided at its upper end on one side with a lug extension 98 adapted to engage the wall portion 100 of the slider to form a stop means therefor for limiting the outward motion of the locking member L'.

In this structural modification of the invention the resilient arms 50' and 52' are also under an initial tension, tending to contract the rigid and resilient arms of the locking member, the tension being derived from the sliding and pressure engagement exerted in the branches of the slider channel by the slide fastener elements f', f' moving against the free ends of the resilient arm branches 94 and 96 as is clearly shown in Figs. 4 and 5 of the drawings. The force exerted may be a direct pressure or a frictional force, or a composite of both. In this form of the invention the locking member comprises in effect a two-armed lever fulcrumed on the slider, one arm being the locking arm of the lever projecting into the slider channel terminating in a locking tooth, and the other arm of the lever comprising the resilient arm which terminates in the point of lever application, namely, the point of engagement with the slide fastener elements in the branch channels. This point of lever application exerts the force which tensions the resilient arms causing the lever to rock on its fulcrum automatically into the locking position. A pull in either direction on the pull device 74 operates to rock the lever or locking member L' in its opposite direction to disengage the locking teeth and move the slider to open position. In the lock slider disclosed in the Mikulas and Jones Patent 2,360,437, the

pressure component of this applied force is increased by causing the stringers to bend out of their normal path, this placing the stringers under a natural resilience. In the structure shown in Figs. 4 and 5 of the present invention, sufficient acting pressure may be obtained without causing any deflection in the movement of the stringers, the force being obtained mainly by the resilient action and movement of the resilient arms of the locking member.

However, the principles of the construction disclosed in Figs. 1 to 5 may be further combined with those of the Mikulas and Jones Patent 2,360,437 by additionally causing the stringers to be deflected out of their normal paths and thus produce a resiliency therein, and this is illustrated in the modification shown in Figs. 6 and 7 of the drawings. This modification is substantially the same as that shown in Figs. 4 and 5 with the exception to be noted and, therefore, similar parts are designated by similar reference characters differentiated, however, by the exponent 2. In this modification, to increase the pressure component at the point of application, a depression or cavity 102 is provided in the rear wing 20² arranged opposite the upper free ends of the resilient branch arms 94² and 96² which latter are formed with channel protruding enlargements such as 104 (see Fig. 7). With the provision of the depression 102, the stringers bend out of their normal path and the slide fastener elements are deflected into this depression, and this deflection, due to the natural resilience of the stringers, causes the fastener elements to contact or engage the points of application 104 with an increased pressure. This, combined with the resilience of the arms 50² and 52² produces a firmly acting lock slider.

The making and using of the lock slider of the present invention and the advantages thereof will in the main be fully apparent from the above detailed description thereof. In all exemplified structural forms of the invention the lock slider is composed, except for the hinge pintle, of three elements, namely, the slider, the locking member, and the pull device. These three elements are so designed and constructed that they are capable of being most conveniently and quickly assembled. The locking member is formed as a unitary piece and preferably its three parts, namely, the locking arm, the detent (or detents) and the spring arm (or spring arms), are formed integrally and preferably shaped (as are all of the parts of the slider) out of sheet stock. This locking member is so designed that it may be readily mounted on the front wing of the slider. In the construction thus provided, despite the limitations imposed by the small space available on the slider, ample operating leverages are obtained for effecting both the automatic locking operation and the unlocking operation of the slider. Thus the leverage of the rigid locking arm of the slider is an extensive one and extends over a substantial, such as the greater part, of the slider length, and the leverage for the resilient arm or arms thereof is also an extensive one and extends over a substantially similar length of the slider. In all of the structural forms the resilient action is obtained by contracting the arms of the locking member, and the force for producing this contraction may be obtained either by an engagement derived from a part of the slider wall or from the moving slide fastener elements themselves.

While we have shown and described preferred

forms of our lock slider it will be apparent that changes may be made therein without departing from the principles thereof and from the spirit of the invention defined in the following claims.

We claim:

1. An automatic lock slider for a slide fastener comprising, a slider body having front and rear wings spaced to provide a slider channel for the slide fastener stringers, and a locking member mounted on said front wing, said locking member comprising a front arm and a rear arm united together at their bottom ends and free at their other ends, said arms being movable resiliently one with respect to the other, said locking member having a detent adjacent its bottom end projecting into the slider channel, the free end of the front arm being fulcrumed on the slider front wing, and the free end of the rear arm extending to a point upwardly of said fulcrum of the front arm so that a force applied to the upward portion in a direction towards said front arm will tend to contract said arms to move the locking member about its front arm fulcrum to locking position, and means connected to said locking member for moving the same about its said front arm fulcrum in opposition to said force to move the locking member to unlocking position.

2. An automatic lock slider for a slide fastener comprising, a slider body having front and rear wings spaced to provide a slider channel for the slide fastener stringers, and a locking member mounted on said front wing, said locking member comprising a front arm and a rear arm united together at their bottom ends and free at their other ends, said arms being movable resiliently one with respect to the other, said locking member having a detent adjacent its bottom end projecting into the slider channel, the free end of the front arm being fulcrumed on the slider front wing, and the free end of the rear arm extending to a point upwardly of said fulcrum of the front arm and engaging with an adjacent part of said wing to contract said arms whereby the engaging force applied thereto will move the locking member to locking position, and means connected to said locking member for moving the same in opposition to said force to move the locking member to unlocking position.

3. An automatic lock slider for a slide fastener comprising, a slider body having front and rear wings spaced to provide a slider channel for the slide fastener stringers, and a locking member mounted on said front wing, said locking member comprising a front arm and a rear arm united together at their bottom ends and free at their other ends, said arms being movable resiliently one with respect to the other, said locking member having a detent adjacent its bottom end projecting into the slider channel, the free end of the front arm being fulcrumed on the slider front wing, and the free end of the rear arm projecting into the slider channel and extending to a point upwardly of said fulcrum of the front arm for engagement at said upward portion by fastener elements on said stringers whereby the engaging force so applied thereto will move the locking member to locking position, and means connected to said locking member for moving the same in opposition to said force to move the locking member to unlocking position.

4. An automatic lock slider for a slide fastener comprising, a slider body having front and rear wings spaced to provide a slider channel for the slide fastener stringers, and a locking member

mounted on said front wing, said locking member comprising a front arm and a rear arm connected at their bottom ends and free at their other ends, said arms being movable resiliently one with respect to the other, said locking member having a detent adjacent its bottom end projecting into the slider channel, the free end of the front arm being fulcrumed on the slider front wing, and the free end of the rear arm projecting into the slider channel and extending to a point upwardly of said fulcrum of the front arm for engagement at said upward portion by fastener elements on said stringers whereby the engaging force so applied thereto will resiliently move the locking member to locking position, and means connected to said locking member for moving the same in opposition to said force to move the locking member to unlocking position.

5. The automatic lock slider of claim 1 in which the front arm comprises a rigid elongated cap having a front wall and side walls, and in which the rear arm is resilient and is united to one of said side walls.

6. The automatic lock slider of claim 1 in which the front wing is provided with a lug for mounting the locking member, in which the front arm of the locking member comprises a rigid elongated cap fulcrumed on said lug and having a front wall and side walls, and in which the rear arm comprises two resilient arm branches united, one to one of said side walls, and the other to the other of said side walls.

7. The automatic lock slider of claim 2 in which the front arm comprises a rigid elongated cap having a front wall and side walls, and in which the rear arm is resilient and is united to one of said side walls.

8. The automatic lock slider of claim 3 in which the front arm comprises a rigid elongated cap having a front wall and side walls, and in which the rear arm is resilient and is united to one of said side walls.

9. The automatic lock slider of claim 4 in which the front arm of the locking member comprises a rigid elongated cap having a front wall and side walls, and in which the rear arm comprises two resilient arm branches united, one to one of said side walls, and the other to the other of said side walls.

10. The automatic lock slider of claim 4 in which the front wing is provided with a lug for mounting the locking member, in which the front arm of the locking member comprises a rigid elongated cap fulcrumed on said lug and having a front wall and side walls, and in which the rear arm comprises two resilient arm branches united, one to one of said side walls, and the other to the other of said side walls.

11. The automatic lock slider of claim 1 in which the front arm comprises a rigid elongated cap having a front wall and side walls, in which the rear arm comprises two resilient arm branches united, one to one of said side walls, and the other to the other of said side walls, in which said detent is located on one of said arm branches, and a locking detent on the other of said arm branches.

12. An automatic lock slider for a slide fastener comprising, a slider body having front and rear wings spaced to provide a slider channel for the slide fastener stringers, and a locking member mounted on said front wing, said locking member comprising a front arm and a rear arm connected at their bottom ends and free at their other ends, said locking member having a detent

adjacent its bottom end projecting into the slider channel, the free end of the front arm being fulcrumed on the slider front wing, and the free end of the rear arm projecting into the slider channel and extending to a point upwardly of said fulcrum of the front arm for engagement at said upward portion by fastener elements on said stringers whereby the engaging force so applied thereto will move the locking member to locking position, and means connected to said locking member for moving the same in opposition to said force to move the locking member to unlocking position.
